PARAFFIN SCRAPING TOOL

Lloyd Lee Ottis Cranford, Baton Rouge, La.

Application September 18, 1940, Serial No. 357,327

5 Claims. (Cl. 166—18)

The present invention relates to tools and more particularly to an oil well tool for scraping or removing paraffin or other accumulations from the casing or tubing thereof.

In many oil wells paraffin or other accumulations collect on the inner walls of the well casing or tubing and seriously impairs and obstructs the free flow of oil therethrough.

It is an object of the present invention to provide a novel scraping tool for cleaning the walls of the well tubing in a rapid and efficient manner.

A further object of the invention is to provide a device of this character which will easily cut through and remove heavily caked material encrusted on the walls of the well tubing.

Another object of the invention is the provision of a tool of this character which is of simple and inexpensive construction, efficient and durable in use.

With the foregoing and other objects in view, the invention will be more fully described hereinafter, and will be more particularly pointed out in the claims appended hereto.

In the drawing wherein like symbols refer to like or corresponding parts through the several views.

Figure 1 is an elevation view of a well scraping tool embodying this invention.

Figure 2 is an enlarged transverse sectional view taken on line 2—2 of Figure 1.

Figure 3 is a similar view taken on line 3—3 of Figure 1, the parts shown in elevation.

Figure 4 is a similar sectional view taken on the line 4—4 of Figure 1.

Figure 5 is an enlarged cross-sectional view taken along the line 5—5 of Figure 1.

Referring more particularly to the drawing, the numeral 10 designates an elongated body or rod which is tapered from its upper end to its lower or leading end, as illustrated in Figure 1. The upper end of the rod 10 is provided with a reduced and threaded extension 11 for removable connection to a suitable drill stem, anchor bar or other actuating member 12. A groove 13 is disposed in the upper end of the rod 10 below the coupling extension 11 to permit fishing of the tool from the well when necessary.

A series of four identical knives 14 are disposed longitudinally of the rod 10 at a point adjacent to but spaced from the lower or leading end of the rod. The knives 14 are equally spaced about the rod or shaft 10 in horizontal alignment and are semi-elliptical in shape, being set into longitudinal slots in the body of rod with

their curved edges sharpened and extending outwardly from the surface of the rod. Screws 15 secure the knives 14 in the rod slots, as seen in Figures 1 and 4.

5 A set of four scraping blades 16 are secured to the rod 10 in horizontal positions, said blades being equally spaced a substantial distance apart. The upper blade 16 is spaced a substantial distance below the top of the rod 10 while the lower blade 16 is spaced a substantial distance above the group of knives 14. A knife 17, identical with knives 14, is secured in a slot below each of the blades 16 in same manner as knives 14, but each knife 17 is spaced 90° about the circumference of the rod from the next adjacent knife 17, as illustrated in Figure 1. As the rod 10 is tapered from the top to the bottom, the knives 17 project radially beyond the knives below. Each knife 17 is disposed in longitudinal alignment with one of the knives 14.

10 Each of the blades 16 is of arcuate shape, extending through an arc of about 240° and may be formed by bending a steel band to the requisite arcuate or circular form. A reinforcing bar 18 is welded or otherwise rigidly attached between the open ends of the blade near the rear edges thereof. This bar 18 is bolted as at 19 within a transverse slot in the surface of the rod 10, whereby the center of the bar is flush with the longitudinal surface of the rod. Thus the bar 18 not only reinforces the blade 16 but also permits the blade to be spaced an equal distance at all points from the rod.

15 The blades 16 are beveled from the inside to the top and from the inside to the bottom to provide top and bottom sharpened cutting edges as illustrated in Figure 1.

20 This design and arrangement results in the paraffin being shaved from the walls of the tubing and as the same is shaved it passes readily behind the blades and is, of course caught in the stream of flowing oil and carried away.

The blades 16 are also spaced about the rod at points 90° apart and the center of each blade 25 is disposed in vertical alignment with the knife 17 immediately below it. The blade 16 at the upper end of rod 10 is radially wider than the next blade having the same radius as the bore of the well tube, and the blades are progressively smaller approaching the lower end of rod 10.

25 In operation the rod 10 is lowered within the well casing and the knives 14 will slice or cut into the paraffin or other accumulation caked on the walls of the casing. The knives 17 will enter the same cuts, slicing them deeper, while,

as the lowering movement is continued, the scraping blades will shave or cut in thin layers the material previously sliced by the knives 14 and 17, and allowing same to pass freely behind the blades.

Due to the progressive change in radial projection of the knives and blades 16, each knife will cut deeper than the one preceding it and each blade 16 will shave or scrape closer to the casing wall than the blade preceding until the foreign matter or accumulation has been completely removed from the casing.

While the blades 16 will also shave or scrape the walls on the upward movement of the tool, the progressive cutting and scraping of the blades and knives is relied on to principally to easily and effectively remove the caked material from the casing walls. Without this progressive action of cutting and scraping deeper and deeper as the tool progresses in its downward stroke, the caked material which collects on the walls of the casing offers too great of a resistance to be removed effectively by ordinary scraping methods.

Although the knives and blades illustrated are in groups of four spaced 90° apart, they may be obviously of any desired number, preferably equally spaced about the circumference of the rod 10.

An important feature of this invention is the action of longitudinally slicing or cutting the caked material before each successive scraper blade is brought into play, and the progressive deepening of the slicing and scraping action.

It is obvious that various changes and modifications may be made in the details of construction and design of the above specifically described embodiment of this invention without departing from the spirit thereof, such changes and modifications being restricted only by the scope of the following claims:

What is claimed is:

1. In a well scraper, an elongated body member, a series of slicing knives with longitudinally arranged cutting edges secured on said body member adjacent the leading end thereof, said knives extending radially from the body member in longitudinally spaced staggered relation about its circumference, and a series of transverse scraping blades secured to the body member above the slicing knives, said scraping blades and slicing knives being spaced apart longitudinally of the body member in alternate arrangement thereon, said scraper blades being disposed in staggered overlapping relation to one another and having arcuate scraping edges, each scraping blade of the series extending radially beyond the scraping blades disposed between it and the leading end of the body member.

2. In a well scraper, an elongated body member, a series of slicing knives with longitudinally arranged cutting edges secured on said body member adjacent the leading end thereof, said knives extending radially from the body member in longitudinally spaced staggered relation about its circumference, and a series of transverse scraping blades secured to the body member above the slicing knives, said scraping blades and slicing knives being spaced apart longitudinally of the body member in alternate arrangement thereon, said scraping blades being dis-

posed in staggered relation and having arcuate scraping edges, each scraping blade of the series extending radially beyond the scraping blades disposed between it and the leading end of the body member, and a knife with a longitudinally disposed radially extending slicing blade arranged in spaced relation ahead of each scraping blade and in alignment with the central portion of said blade.

- 5 3. In a well scraper, an elongated body member, a series of slicing knives with longitudinally arranged cutting edges secured on said body member adjacent the leading end thereof, said knives extending radially from the body member in longitudinally spaced staggered relation about its circumference, and a series of transverse scraping blades secured to the body member above the slicing knives, said scraping blades and slicing knives being spaced apart longitudinally of the body member in alternate arrangement thereon, said scraper blades being disposed in staggered relation and having arcuate scraping edges, each scraping blade of the series extending radially beyond the scraping blades disposed between it and the leading end of the body member, and a knife with a longitudinally disposed, radially extending slicing blade arranged in spaced relation ahead of each scraping blade and in alignment with the central portion of said blade.
